METAL PIN RACK FOR FABRIC STRETCHING MACHINES

Gustav Möhring, Stuttgart, Germany, assignor to Famatex G.m.b.H., Stuttgart-Kornwestheim, Germany, a firm

Application August 29, 1955, Serial No. 531,046

Claims priority, application Germany September 3, 1954

11 Claims. (Cl. 26—62)

The present invention relates to fabric stretching machines, and more particularly to a pin rack made of metal which is used on fabric stretching machines especially in the treatment of fabrics and the like with high temperatures which must be maintained within narrow limits. It is difficult when carrying out such treatment to ensure that the high temperature is uniform over the entire width of the web, because the tenter chains and the pin racks carried thereby cool down outside the drying chamber and, in running through the drying chamber, must be again heated, so that the temperature at the edges of the cloth is subjected to considerable fluctuations and mostly differs from the temperature in the middle portion of the cloth web. In order to reduce the influence of the cold chain it has already been proposed to introduce a heat insulating connection between pin rack and chain link. It has been found that the objection is reduced by this measure but not overcome.

The object of the invention is to provide a metal pin rack having a plurality of pins rigidly fixed in the metal pin rack and adapted to pierce the edge of a cloth web, which metal pin rack comprises a metal rack plate, carrying the pins, and spacing means preventing heat-conducting contact between said rack plate and said cloth web pierced by the pins.

In particular the spacing means may consist of a protective layer with low heat-conductivity applied on to the metal rack plate, or a stepped enlargement of the feet of the pins themselves, or peg-like projections from the plate of the pin rack in which projections the pins of the pin rack are located and which can themselves be fitted in bores in the rack plate, or finally they may consist of shorter spacer pins arranged between the pins on the pin rack.

With such pin racks it is possible, for example, when heat setting fabrics made of all-synthetic threads in a high temperature section of a drying machine to attain at temperatures between 190 and 250° C., a sufficiently good and uniform quality of goods, whereas with the pin racks hitherto known it can always be observed that the pierced edges of the fabric are not so thoroughly heat set as the middle portions thereof. Also when rendering woven fabrics crease-resistant, for which high temperatures are exclusively used, the advantages of the pin rack according to the invention will be particularly apparent.

Several preferred embodiments of the invention are illustrated by way of example in the accompanying drawing, in which:

Fig. 1 is a perspective view of a pin rack with a special form of pins;

Fig. 2 is a section of a part of a pin rack with pins fitted in pegs projecting from a rack plate;

Fig. 3 is a section of a part of a pin rack with pins inserted in pegs projecting from the rack plate and secured in bores provided therein, and

Fig. 4 shows a pin rack with spacers arranged between the individual pins.

The metal pin rack according to Fig. 1 consists of a

2

metal rack plate 1 provided with a number of pins 2 each comprising a point which, according to the invention, projects with a shoulder or step from a pin foot 3 of larger diameter.

5 According to Fig. 2 the rack plate 1 has at the points where pins 2¹ are arranged, peg-like projections 4, preferably with flat tops are made in one piece with the rack plate 1 by pressing, casting or the like. The pins 2¹, which in this case are of the known shape, are introduced, preferably pressed, from below into bores in the rack plate 1, a bore being provided in the middle of each projection for this purpose.

According to Fig. 3 the pins constructed in known manner are fitted in separate, preferably cylindrical, but if 15 desired also conical pegs 5, which themselves are fitted in suitable bores 6 in rows or other suitable arrangement in the rack plate 1. The conical pins are fixed in the pegs 5 and these pegs 5 in turn are fixed in the rack plate 1, preferably by pressing. The needles are pressed into the pegs before the pegs are inserted in the rack plate 1. The pressing in of the pins causes the pegs to expand slightly which assists in giving the pegs a better hold when being pressed into the plate.

The pegs and pins can be made for example from stainless steel or the like. In most cases it will suffice to make the rack plate 1 from a less high grade material, such as tin-plated brass or the like.

The bores for securing the pins 2, 2¹ in the plate 1 or in the pegs 5 are at an incline to the surface of the plate or 30 the axis of the pegs to correspond with the desired inclination of the pins.

The pegs 5 can also be made of heat insulating material.

According to Fig. 4 short spacer pins 7 are arranged between each two neighboring pins 2¹ of usual shape, 35 these spacer pins being blunt and, as shown in Fig. 4, are preferably provided with domed heads 8.

In all cases direct contact between the cloth web and the wide surface of the rack plate 1 is reliably avoided.

When using an insulating protective layer as spacing 40 means a layer 9 of synthetic resin or other material possessing favorable thermal properties in the sense of the invention can be applied on to the metal part of the rack plate 1, as indicated in Fig. 1. The mechanical strength of the protective layer is not a determining factor because 45 the pins are held in the metal rack plate 1 of the pin rack. Of course, it is possible to use the protective layer 9 also in connection with metal pin racks as are shown and described with reference to Figs. 2, 3 and 4.

From the above detailed description of the invention, 50 it is believed that the construction will at once be apparent, and while there are herein shown and described several preferred embodiments of the invention, it is nevertheless to be understood that minor changes may be made therein without departing from the spirit and scope 55 of the invention as claimed.

I claim:

1. A metal pin rack for use in fabric stretching machines employing tenter chain means for conveying a fabric web therethrough, said metal pin rack comprising 60 a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a step-like enlargement extending from the end of the pin inserted in said metallic rack plate and projecting beyond said plate toward the pin point so as to hold said fabric web spaced from said plate.

2. A metal pin rack for use in fabric stretching machines employing tenter chain means for conveying a fabric web therethrough, said metal pin rack comprising a 70 metallic rack plate, a plurality of pins fixed in said rack

plate and adapted to pierce the edge of a fabric web, and peg-like spacing means preventing heat-conducting contact between said metallic rack plate and said fabric web pinned thereon, said spacing means consisting of a plurality of peg-like projections on the surface of the rack plate, in which projections the pins are fitted.

3. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of pegs formed separate from the rack plate and the pins and each carrying a pin and being inserted in a suitably located bore in the rack plate.

4. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of pegs each carrying a pin in a bore and being inserted in a suitably located bore in the rack plate, the bores in the pegs carrying the pins being arranged at an incline to the surface of the rack plate and to the peg axis corresponding to a desired inclination of the pins to the rack plate surface.

5. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of pegs each carrying a pin and exchangeably inserted in a bore in the rack plate.

6. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of pegs each carrying a pin and inserted in a bore in the rack plate, said pegs being made from heat insulating material.

7. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plural-

ity of peg-like projections formed in one piece with the rack plate on the surface thereof and each carrying a pin.

8. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of short spacer pins arranged between the rack pins.

9. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of short spacer pins arranged in alternating relation to the rack pins.

10. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and peg-like spacing means preventing heat-conducting contact between said metallic rack plate and said fabric web pinned thereon, said spacing means consisting of a plurality of short spacer pins provided with domed heads and arranged between the rack pins.

11. A metal pin rack for use in fabric stretching machines employing tenter chain means for conveying a fabric web therethrough, said metal pin rack comprising a metallic rack plate, a plurality of pins fixed in said rack plate and adapted to pierce the edge of a fabric web, and a plurality of peg-like spacing members adapted to prevent heat-conducting contact between said metallic rack plate and said fabric web pinned thereon.
